PICTURE FRAME

William H. Ott, Cincinnati, Ohio

Application January 22, 1949, Serial No. 396

Term of patent 3½ years

(Cl. D29—20)

To all whom it may concern:

Be it known that I, William H. Ott, a citizen of the United States and a resident of Cincinnati, in the county of Hamilton and the State of Ohio, have invented a new, original, and ornamental Design for a Picture Frame, of which the following is a specification, references being made to the accompanying drawings, forming a part thereof.

Fig. 1 is a front elevational view of a picture frame embodying my new design.

Fig. 2 is a top plan view of the picture frame illustrated in Fig. 1.

Fig. 3 is a side elevational view of the picture frame.

I claim:

The ornamental design for a picture frame, substantially as shown.

WILLIAM H. OTT.
